G. R. LIVERGOOD

PIPE ENGAGING SLIP

Filed Jan. 21, 1922

GERALD R. LIVERGOOD, Inventor

By *Jesse R. Stone*
his Attorney

UNITED STATES PATENT OFFICE.

GERALD R. LIVERGOOD, OF HOUSTON, TEXAS.

PIPE-ENGAGING SLIP.

Application filed January 21, 1922. Serial No. 530,800.

To all whom it may concern:

Be it known that I, GERALD R. LIVERGOOD, a citizen of the United States, residing at Houston, Harris County, Texas, have invented a certain new and useful Improvement in Pipe-Engaging Slips, of which the following is a full, clear, and exact description, such as will enable others skilled in the art to which it appertains to make and use the same.

My invention relates to pipe-engaging slips adapted particularly to fit within a tapered seat of a well drilling rotary and to grip the drill pipe and sustain the load of pipe suspended in the drill hole.

The construction of this slip is a further improvement and development of the slip shown in my prior Patent No. 1,381,074 granted June 7th, 1921.

An object of my invention is to provide a pipe engaging slip for rotaries of drilling rigs which may be made up of a plurality of jaws held together and operable as a unit, and which will need no plate or securing member at the lower end thereof.

Another object is to provide means of securing the jaws in a slip of this character flexibly together in such manner as to prevent the accidental loss of one of the jaws during operation.

Another object is to provide means to hold the jaws assembled together and to prevent undue rotative movement of any one of the jaws relative to the supporting frame and to the other jaws.

Referring to the drawing herewith, wherein I have applied like numerals to like parts as far as possible throughout the several views, Fig. 1 is a transverse section of my improvement taken on the line 1—1 of Fig. 2. Fig. 2 is a front elevation of my improved multiple slip, some parts being broken away for greater clearness. Fig. 3 is a top plan view of my device. Fig. 4 is a central longitudinal section through a drilling rotary showing my slip employed therein, and Fig. 5 shows a top plan and a front elevation of the key or tenon employed in my improvement.

It is sometimes found to be of some disadvantage in multiple jaw slips to provide a plate, or other securing means, at the lower ends of the jaws. This is especially so on some of the larger sizes of slips. It has therefore been my effort in this improvement to provide means which will se-

cure the jaws to a holding means and to allow free play of the jaws relative to each other and to the holder, and to do this without the necessity of any securing means at the lower ends. In the drawing I have shown the slip made up of a plurality of separate jaws 6. I have contemplated the employment of several of these jaws on each holding means, and I have shown a set comprising four separate jaws and these jaws arranged in a semi-circular group so as to grip one-half of the pipe. By so doing, I find it necessary to use but two slips—each of them being a compound slip made up of the four jaws as shown. It is obvious, however, that a different number of jaws could be employed in each group and I do not wish, therefore, to limit myself to this particular number.

Each of the jaws 6 is tapered on its outer surface to fit within a tapered seat 7 of a rotary table 8 as shown in Fig. 4. The inner surface of the jaw is toothed at 9 to adapt the same to grip the pipe, and it will be noted that the teeth are inclined somewhat upwardly for this purpose. Each of the jaws is also provided with a threaded recess 10 at its upper end into which may be secured a bolt or pin 11 threaded at its upper end to receive a nut 12 by means of which it may be secured adjustably to the holder. Each of the jaws is also provided with a slot or mortice 13 on its opposite sides. These slots extend from the upper end downwardly along the side of the jaw to a point somewhat below the middle thereof. This slot is a key-hole slot—that is, it has a rounded inner portion as shown at 14, and a narrow slot or groove 13' leading therefrom. Each of these mortices or slots is arranged in a position exactly opposite the slot in the adjacent jaw so as to receive a key or tenon 15, shown particularly in Fig. 5. This key has a narrow central portion and two rounded and enlarged sides 16 thereon. As shown in the plan view of Fig. 5 it will be noted that the rounded edges 16 are somewhat elliptical in shape so that they will be received loosely within the rounded portion 14 of the key-way or mortice, thus allowing lateral play of the jaws relative to each other. Midway of the key 15 I form a recess 17 on each side of the said key by cutting away a part thereof, as shown particularly in Fig. 5. When the key is then placed in position as shown in

Fig. 1, it will serve to secure the two adjacent jaws together. By then boring a hole through the jaw on a line with the recess 17 of the key I am enabled to insert a short 5 plug or pin 18 therethrough so as to prevent vertical movement of the tenon or key within the slot beyond a certain point, this play being limited by the upper and lower edges of the recess 17 in the key. These 10 pins 18 extend entirely through the jaw and may be driven into or from this position by means of a punch.

In addition to the securing of the jaws together centrally by means of the keys 15, 15 I provide an upper semi-circular plate 19. This plate has openings 20 therein at spaced intervals to receive the pins 11 projecting upwardly from the jaws. The openings 20 are somewhat larger than the pins 11, as 20 shown at the left in Fig. 3 so that there will be a loose play of the pin within the opening. This opening 20 furnishes a bearing for the pin, and to strengthen this bearing and the plate I extend a lug 21 downwardly 25 from the plate at each of the openings as shown in Fig. 2. Thus the lug spaces the jaws somewhat from the upper plate and also furnishes a better bearing for the pins 11, as will be obvious. On the upper face of 30 the plate 19 I form two upwardly extending lugs 22—one of these lugs at each side of the central portion of the plate. These lugs are formed with a central opening therethrough to receive the outwardly curved end 35 of a handle member 23 of the usual design.

The operation of this improved slip will now be obvious. When the pipe is ready to be seized by the slip the said slip is inserted within the tapered seat 13 of the rotary 40 table and the pipe allowed to rest upon the said slips. The frictional contact of the jaws with the pipe will draw the slips firmly downwardly into the seat 7 and will thereby clamp them against the pipe in such manner 45 as to hold the same firmly. As each of the jaws has but a short face in contact with the pipe it will not tend to seize the pipe in such way that it may not be easily released. Each of the jaws having free play relative 50 to the holder and to each other, will adjust themselves to irregularly shaped pipe and to pipe in different positions. It will be noted that the pins 11 project upwardly through the plate so as to allow a loose 55 vertical play of the jaws relative to the said plate and the fit of the key 15 in the jaws is so loose that a great deal of freedom is thereby allowed.

When the jaws are made up, it is intended 60 that they shall be made in quantities and in such manner that they may be interchangeable. For this reason I have shown the outermost jaws of each set formed with the slots 13 formed therein in the same manner as are the slots in the other jaws. It

will be obvious, however, that these outermost slots will be of no use during the operation of the slip and are only formed therein to secure the interchangeability of the jaws. When the pins or plugs 18 are inserted 70 through the openings 17 in the keys 15, in practice it will be obvious that if one or more of the jaws become loosened due for instance to the loss of one or more of the nuts 12 on the upper ends of the pins, or to the shearing off of one of the pins, it will be impossible for the jaw to be lost from the holder and drop into the well. Each of the keys forms a sort of link, as in a chain, 75 acting to tie each jaw flexibly to the adjacent jaw. The slip as thus formed is thereby made safe for use and the liability of junking the hole due to the dropping of one of the jaws therein is overcome.

Having thus described my invention, the further advantages of which will be obvious to one skilled in the art, what I claim as new and desire to protect by Letters Patent is:

1. In a slip for rotaries comprising a plurality of pipe engaging jaws, means to hold 90 said jaws loosely together comprising a segmental plate, a pin on each jaw slidable in said plate and having a limited movement relative thereto, bearing means for said pins, mortices in the adjacent faces of each of said jaws, a key fitting loosely in the mortices of two adjacent jaws, and serving to connect said jaws flexibly together and means to retain said keys in said mortices. 95

2. In a slip for rotaries comprising a plurality of pipe engaging jaws, means to hold 100 said jaws loosely together comprising a curved plate having bearing openings therein, pins on said jaws fitting loosely in said openings, mortices on the side faces of the jaws, and keys having enlarged ends fitting slidably in the mortices of two adjacent jaws and acting to hold them flexibly together. 105

3. In a slip for rotaries comprising a plurality of pipe engaging jaws, means to hold 110 said jaws loosely together comprising an upper plate, means to secure said jaws loosely to said plate and means to secure said jaws flexibly to each other comprising a key having enlarged side portions adapted to fit 115 within keyhole-shaped mortices in the adjacent sides of two of said jaws and means to retain said keys loosely in said mortices.

4. In a slip for rotaries comprising a plurality of pipe engaging jaws means to hold 120 said jaws loosely together comprising an upper plate to which each jaw is slidably connected and keys between the adjacent jaws fitting in mortices in the sides of said jaws, and means to prevent removal of said 125 keys including pins in said jaws adapted to pass through openings in the sides of said keys in the manner described.

5. A slip for rotaries having a plurality of pipe engaging jaws, means to hold said jaws 130

flexibly together comprising an upper plate having a handle thereon, pins on said jaws loosely engaging said plate, and separate means connecting each jaw flexibly to the 5 jaw adjacent thereto.

6. In a pipe engaging device, a plurality of slips, each slip comprising a plurality of separate jaws, means connected to said jaws to move each slip as a unit, and means 10 separate from said jaws and slidably vertically thereon to connect the adjacent sides of each jaw flexibly to the adjoining jaw.

7. In a multiple jaw slip for rotaries, the combination of a plurality of segmental arcuate plates, a plurality of jaws slidably secured to each plate, and separate means connecting adjacent jaws at their sides to hold them flexibly together, and allowing each jaw a limited play to and from adjacent jaws of said slip. 15

In testimony whereof, I hereunto affix my signature, this the 18th day of January, A. D. 1922.

GERALD R. LIVERGOOD.
